UNITED STATES PATENT OFFICE.

CLARK D. BEDWIN, OF LONG BEACH, CALIFORNIA.

WATER HEATER.

1,421,149.

Specification of Letters Patent. Patented June 27, 1922.

Application filed May 5, 1920. Serial No. 379,092.

To all whom it may concern:

Be it known that I, CLARK D. BEDWIN, a citizen of the United States, residing at Long Beach, in the county of Los Angeles and State of California, have invented certain new and useful Improvements in Water Heaters; and I do hereby declare the following to be a full, clear, and exact description of the invention, such as will enable others skilled in the art to which it appertains to make and use the same.

This invention relates to water heaters and more particularly to that type used for household and similar purposes.

15 An object of the invention is to provide an easily assembled and easily cleaned water heater consisting of comparatively few parts.

Another object of the invention is to construct a water heater having a novel water 20 circulating path or route through which the water is passed for intensely heating the same.

Another object of the invention is to produce a water heating unit, the several parts 25 of which can be economically manufactured, and subsequently assembled in a minimum amount of time by unskilled labor.

With these and other objects in view the invention further consists in the arrangement 30 and construction of the several parts hereinafter described and pointed out in the appended claims.

In the accompanying drawings illustrating an embodiment of my heater:

35 Figure 1 is a front view thereof with the front plate removed;

Figure 2 is a vertical sectional view of the heater taken at right angles to Figure 1;

Figure 3 is a rear view of the heater with 40 the back plate removed;

Figure 4 is a horizontal sectional view on the line 4—4 of Figure 1; and

Figure 5 is a perspective view of the assembled water heater illustrating the inlet 45 and outlet connections and the hinged door provided in one side for cleaning and inspection purposes.

Referring to the drawings in which similar reference characters designate corresponding parts in the several views, the heater includes among other things oppositely arranged headers 1 and 2 into which are expanded or otherwise secured the opposite ends of water circulating tubes 3; also 50 co-acting front and back plates 4 and 5, said plates being positioned against the headers

1 and 2 respectively, so as to form a series of intercommunicating chambers producing a novel path of travel for the water.

The headers 1 and 2 are provided with a 60 series of projecting fins or ribs 6 the outer edges of which are preferably machined so that the inner faces of the front and back plates 4 and 5 when abutted against the ribs as shown, serve to form water-tight joints at 65 all points throughout the water circulating chambers. The inner faces of the plates 4 and 5 may also be machined or ground as will be understood.

The arrangement of the projecting ribs 6 70 is novel in that they extend vertically and horizontally thereby dividing the heater into adjacent series of intercommunicating chambers forming predetermined water circulating paths or routes at the front and back of 75 the heater. Referring particularly to Figures 1, 2 and 3, a water inlet chamber 7 is shown as communicating with some of the tubes 3, through which latter the water flows to the rear of the heater into one of a series 80 of chambers 8 arranged upon one side of the back of the heater. From this chamber 8 the water flows through other communicating tubes 3 into one of a series of chambers 9 provided between the ribs 6 at the front of 85 the heater and upon one side thereof as shown. The water flows from the chamber 9 into communicating tubes 3 and discharges into another one of the chambers 8 at the rear of the heater, and from this said chamber 90 8 it continues to pass again to the front of the heater into another one of the chambers 9, and so on until it reaches the top of the heater and empties into a relatively wide chamber 10. The chamber 10 extends across 95 the top of the heater and has communicating therewith some of the tubes 3 which serve to convey the water rearwardly into one of a series of chambers 11 arranged at the rear of the heater adjacent the chambers 8 hereinbefore referred to. From the chamber 11 100 the water passes forwardly through the communicating tubes 3 into one of a series of chambers 12 arranged at the front of the heater adjacent the chambers 9 hereinbefore 105 described.

The water continues to flow downwardly through the tubes 3 and intercommunicating chambers 11 and 12 until it reaches the bottom of the heater, where it empties into a relatively wide chamber 13. This chamber 13 110 extends across the bottom of the heater and

has communicating therewith tubes 3 which serve to convey the water rearwardly into one of a series of chambers 14 arranged at the rear of the heater adjacent the chambers 11, and beneath the chambers 8, above referred to. The water now flows from the chamber 14 forwardly again through the tubes 3 into one of a series of communicating chambers 15 at the front of the heater, 10 adjacent the said chambers 12 and beneath the chambers 9 hereinbefore described. The water continues to flow upwardly through the aforesaid intercommunicating chambers, until it discharges into the outlet chamber 16 arranged at the front of the heater and 15 in close proximity to the inlet chamber 7.

From the foregoing it will be seen that a relatively tortuous path of travel or route of the water is obtained from a comparatively simple construction and that the water is 20 gradually heated to a maximum intensity from the time it is introduced into the heater.

An inlet pipe 17 and an outlet pipe 18 are connected to the chambers 7 and 16 respectively. 25

The relative closeness of location of these connections has been found to be useful in reducing the time that it takes to assemble and connect up the heater, as will be understood. 30

The heater is provided with a hinged door 19 attached to one side of the heater upon hinges 20. The purpose of the door is to facilitate cleaning the heater and to provide 35 means for readily inspecting the same.

A plate 21 forms the opposite side wall of the heater and is detachably secured to the headers 1 and 2 by means of bolts, cap screws or similar fastening devices. 40

A burner 22 is shown at the bottom of the heater for supplying the necessary heat which passes upwardly through the heater contacting with the several tubes and the interior walls.

The heater is provided with a cap or top section 23 of dome or similar shape as shown. 45

The headers 1 and 2 are preferably designed to extend to the bottom of the heater, 50 as shown, and the hinged door 19 and side plate 21 are likewise extended, thereby producing a completely enclosed structure the better to conserve heat.

The fastening devices for the several parts 55 may be bolts or cap screws of standard construction, although it will be understood that various other devices may be employed.

Various changes in the proportion and arrangement of the several parts may be made 60 and I do not limit myself to the exact construction herein set forth.

I claim:—

1. A water heater comprising oppositely arranged headers having a plurality of relatively short projecting ribs upon the outer 65

faces thereof arranged so as to form two sets of headers on each side of the heater, a plate fitted against the ribs of the headers, said plate forming one wall of a series of relatively small water circulating chambers at 70 the front and back of the heater, tubes connecting the corresponding sets of headers for establishing communication with the aforesaid chambers, a water inlet provided at the front midway of the heater and communicating with one of the circulating chambers, and an outlet for the heated water, said outlet communicating with another of said circulating chambers and arranged midway of the heater in close proximity to the afore- 80 said inlet.

2. A water heater comprising oppositely disposed headers, a plurality of relatively short projecting ribs upon the outer faces thereof, said ribs being arranged in vertical and horizontal relation to each other so as to form two vertical sets of headers on each side of the heater, a plate fitted against the headers, said plate being adapted to abut against the said projecting ribs and to form 90 therewith a series of relatively small chambers upon adjacent sides of the heater at the front and back thereof, tubes connecting the corresponding sets of headers and establishing communication with the aforesaid chambers for conveying the water upwardly upon one side of the heater and downwardly upon the adjacent side thereof, an inlet for the water to be heated, and an outlet for the heated water. 95

3. A water heater comprising oppositely disposed headers having a plurality of relatively short projecting ribs upon the outer faces thereof, said ribs being arranged in vertical and horizontal relation to each other 105 and provided with machined edges, a plate fitted against the said edges of the ribs of each header for completing a series of relatively small chambers upon adjacent sides of said vertical ribs at the front and back thereof, relatively wide and shallow chambers at the top and bottom of said heater, and communicating with the aforesaid relatively small chambers, tubes secured to said headers and communicating with the aforesaid chambers, an inlet communicating with one of the chambers aforesaid midway of the heater and upon one side thereof, and an outlet arranged in close proximity to the said inlet, whereby the water is conveyed from the inlet aforesaid upwardly upon one side of the heater, thence downwardly upon the adjacent side of the heater and returned upwardly upon the first mentioned side of the heater to the outlet aforesaid. 110

4. A water heater comprising oppositely disposed headers having a plurality of relatively short ribs, projecting from the outer faces thereof, said ribs forming adjacent series of relatively shallow chambers upon 115 120 125 130

each side of the heater at the front and the back thereof, and relatively wide and shallow chambers at the top and bottom of the heater, said wide chambers being in communication with the aforesaid adjacent series of relatively small chambers, a plate fitted against the ribs upon each header to complete the chambers aforesaid, tubes secured to said headers and communicating

with the chambers, an inlet for the water to 10 be heated, and an outlet for the heated water.

In testimony whereof I affix my signature, in presence of two subscribing witnesses.

CLARK D. BEDWIN.
